Primary Examiner—M. N. Pandozzi*Attorney, Agent, or Firm*—Richard L. Gausewitz; Oppenheimer Wolff & Donnelly LLP**[57] CLAIM**

The ornamental design for a thermos bottle-cup for use in motor vehicles, as shown and described.

DESCRIPTION

FIG. 1 is a top plan view of a thermos bottle-cup for use in motor vehicles;

FIG. 2 is a left side elevational view thereof, the right side elevational view being a mirror image;

FIG. 3 is a front elevational view thereof, as viewed from the left in FIG. 2;

FIG. 4 is a back elevational view thereof, as viewed from the right in FIG. 2; and,

FIG. 5 is a bottom plan view thereof.
The side not shown in FIG. 1 is the mirror image of the side shown therein.
